(57) **CLAIM**

The ornamental design for a stock car air freshener for motor vehicles, as shown and described.

DESCRIPTION

FIG. 1 is a perspective view of a stock car air freshener, showing our new design.

FIG. 2 is a perspective view of a second embodiment thereof; FIG. 3 is a front elevational view on an enlarged scale thereof;

FIG. 4 is a rear elevational view on an enlarged scale thereof;

FIG. 5 is a left side elevational view thereof;

FIG. 6 is a right side elevational view thereof;

FIG. 7 is a top plan view on a reduced scale thereof;

FIG. 8 is a bottom plan view on a reduced scale thereof;

FIG. 9 is a bottom plan view on a reduced scale of a third embodiment thereof; and,

FIG. 10 is a perspective view thereof, on a greatly reduced scale, the broken line drawing of an air vent grille is for illustrative purposes only and forms no part of the claimed design.

The sole difference between the first and second embodiments is the location of the clip that is on the right side of the first embodiment and on the left side of the second embodiment. The sole difference between the third embodiment and the first and second embodiments is the lack of a clip.
